LOOSE LEAF BINDER

Donald McChesney and James Cooper, Solvay,
N. Y., assignors to Hall & McChesney, Inc.,
Syracuse, N. Y., a corporation of New York

Application June 18, 1936, Serial No. 85,956

3 Claims. (Cl. 129—24)

This invention relates in general to loose leaf binders, and more particularly to loose leaf binders of the heavy, rugged type used as record books for the recording of legal documents, such 5 as deeds etc.

An object of the invention is a loose leaf binder of the type referred to embodying an improved structure which will permit the leaves to assume a substantially flat position when the book is 10 opened for inspection.

A further object of the invention is to provide means for shifting the inner portions of the leaves back into right angular relationship relative to the back member of the binder during the 15 closing of the covers.

A further object of the invention is a loose leaf binder of the type referred to, and while possessing the advantages of the objects above mentioned is of neat and attractive appearance, 20 and is particularly durable in use.

The invention consists in the novel features and in the combinations and constructions hereinafter set forth and claimed.

In describing this invention, reference is had 25 to the accompanying drawings in which like characters designate corresponding parts in all the views.

Figure 1 is a plan view of the inner face of 30 our improved binder showing the portion of the covers adjacent the back member open in flat position, and with the leaves removed.

Figure 2 is a cross sectional view taken on lines 2—2, Figure 1, but with the covers swung to closed position.

Figure 3 is a cross sectional view, similar to 35 Figure 2, with the book in open position.

Figure 4 is a cross sectional view taken on lines 4—4, Figure 1, with the covers open at an angle of approximately 45°.

Figure 5 is a perspective view of the post securing housing and contiguous portions of the back and cover members.

Figure 6 is a perspective view of the post securing means carried within the housing shown 45 in Figure 5.

The invention consists generally, of a loose leaf binder having a back member, housings secured to the back member, one extending along each longitudinal edge thereof, the inner sides 50 of the housings extending outwardly at an oblique angle from the inner face of the back member to effect a minimum flexing of the inner portions of the leaves when the covers are opened in flat position, a plurality of leaf posts extending transversely of the back member and in

spaced apart relationship thereto, means carried by the housings for securing the ends of the posts thereto, a cover hinged to each side edge of the back member and being provided with means operable during the closing of the cover 5 to move the leaves into right angular relationship to the back member.

In the illustrated embodiment of our invention, the back member is composed of a metallic tube having walls 10, 11, slightly spaced apart and 10 formed slightly arcuate. The outer wall 11 is provided with an outer finishing layer 12 of suitable material, such as leather, with the edges of the outer layer 12 extending inwardly over the inner wall 10, as shown in Figures 1 to 4. The 15 back member further includes a plate 13 secured at intervals to the tubular structure 10, 11, by posts 14. The plate 13 is arranged in spaced apart relationship to the tubular structure 10, 11.

The leaves 15 are detachably secured at their 20 inner ends to the binder by leaf posts 16 which extend transversely of the back member and in spaced apart relation to the plate 13. The leaf posts 16 are detachably secured at their ends to the back member. A housing 18 is secured to each longitudinal edge of the back member, and is provided with means operable to engage the 25 ends of the posts 16.

The housing 18 are formed integral with the plate 13. That is, the side edges of the plate 13 are bent, or formed up in the shape of an oblong or elongated loop to form the hollow housings. However, the housings may be formed separately and secured to the plate 13 in any desirable manner. The housings 18 extend outwardly from the inner face of the back member or plate 13 at an oblique angle relative to the plate 13, and the housings and plate 13 form a trough member having diverging side walls. That is, the housings 18, or at least the inner sides of the same, diverge outwardly as illustrated in Figures 2 to 4 inclusive. The purpose of this particular arrangement of the housings 18 is to reduce the arc, or radius, of the inner portions of the leaves 15 when the book 30 is in flat open position, as shown in Figure 3.

Heretofore, insofar as we are aware, it has been customary to arrange the post securing housings at substantially right angles to the inner face of the back member. This causes the inner portions of the leaves to retain a right angle relationship to the back member and accordingly, results in the leaves flexing over an arc or radius of considerable dimension, causing the top leaves 35 on each side of the stack to tend to move to a 40 45 50 55 60 65 70 75 80 85 90 95 100 105 110 115 120 125 130 135 140 145 150 155 160 165 170 175 180 185 190 195 200 205 210 normal closed position and making it difficult to inspect, or read, the written matter along the inner portions of the leaves. This results in persons inspecting, or making abstracts from the book, attempting to force the inner portions of the leaves apart, often damaging the inner edges of the leaves engaged by the leaf posts 16.

As illustrated in Figure 3, due to the particular arrangement and construction of the back member, the binder, when opened, lies in a substantially flat horizontal position, with the back extending in substantially the same plane as the outer surface of the covers 20 when the book is opened on a flat surface and the leaves 15 readily part and flex on a comparatively small radius, whereby the entire surface of the leaf written upon can be conveniently inspected.

The covers 20 are preferably of laminated construction comprising inner and outer layers 21, 22, with a metallic plate 23 secured between the laminations 21, 22, and extending outwardly from the inner longitudinal edge of the cover and formed with pintle receiving eyes 24. The housings 18 are formed, or provided with complementary eye members 25 which, together with the eye members 24, form a piano type hinge between the covers and the back member. In the structure illustrated, this hinge is assembled on a pintle rod 26 located along the longitudinal edge 30 of the back member adjacent the bottom of the housings 18 and in spaced relation to the tubular structure 10, 11. The covers 20 are provided with an outer finishing layer 27 of material similar to the outer finishing layer 12 on the back member, 35 and this outer layer 27 extends between the lateral edges of the tubular structure 10 and 11 and the hinged joint of the cover, as illustrated in Figures 2 to 4. With this structure, the hinged joint of the cover is concealed and the finished 40 appearance of the binder continued throughout the covers and the back member.

The hinge plate 23 of the covers 20 is offset or curved outwardly as at 39 to provide a pocket or recess to receive the housings 18 when the 45 covers are in closed position, as indicated in Figure 2.

Preferably, one or both of the housings 18 is provided with means for detachably securing the ends of the posts to the housings and the back 50 member. As here illustrated, each housing 18 contains a slide member 31 which is movable axially of the housing and extends through one end of the housing, and is provided with a suitable knob or handle 32 by which the slide 31 55 may be manually manipulated. The slide 31 is also provided with a plurality of post engaging pintles 33 which are so arranged that when the slide 31 is moved inwardly, the pintles 33 enter apertures in the ends of the posts 16. The housings 18 are provided with a plurality of notches 34 of such width as to receive the ends of the 60 posts 16.

In order that the leaves, and particularly the inner portions of the leaves, may be rearranged 65 in a perpendicular position relative to the back member or plate 13, the covers 20 are provided with means for engaging the leaves and moving them to such position during the closing of the covers. As here shown, the covers 20 are provided on their inner faces with one or more projections 35. These projections may comprise an extension of the inner lamination 21, or may consist of a metallic plate, or the like, secured to the inner side of the covers. The projections 70 75 35 extend through the housings 18, or toward

the cover hinge, and are of such length that they extend downwardly and overlap the inner sides of the housings 18 and preferably, assume a position in a plane intercepting the jointure of the base of the housings 18 with the back plate 13. 5 Due to the fact that the projections 35 extend inwardly beyond the outer edge of the housings 18, the housings 18 are provided with slots or openings 36 of sufficient width to receive the projections 35, and in the structure disclosed the 10 slide member 30 is also provided with complementary cut away portions 37 which are of sufficient length to permit passage of the cover extensions 35 during opening and closing movement of the covers. That is, as the projections 15 35 travel in an arc about the axis of the cover hinge, they pass through the slots 36 and the cut out portions 37 of the slide 30 and engage the outermost leaf on each side of the book, and during the closing of the cover the leaves are 20 thus straightened up and moved to a position at right angles to the back member or plate 13, as indicated by the dotted outline Figure 2.

We have found that the structure described operates efficiently when the housings 18 are 25 arranged on an oblique angle of about 45° relative to the back member. This permits the pages of large record books to assume a substantially flat position, and the continuation of the inner 30 face of the cover in the nature of the projections 35 form an effective and efficient means for rearranging the pages during the closing of the covers.

What we claim is:

1. A loose leaf binder comprising a back member, a housing extending along the longitudinal edge of the back member and extending outwardly at an oblique angle relatively thereto, a plurality of leaf retaining posts being secured at like ends to said housing, a cover hinged to the 40 back member adjacent said housing, said cover being formed on its inner face with leaf engaging projections extending toward said housing, and said housing being provided with notches in its outer edge, said notches being arranged to 45 permit said projections to be moved through said housing during opening and closing of the cover.

2. A loose leaf binder comprising a back member, a pair of housings carried by said back member, said housings extending along the longitudinal edges of said back member and extending outwardly at oblique angles relatively thereto to permit the leaves of the binder to lie substantially flat when the binder is open, a plurality of leaf retaining posts extending transversely of 55 said back member in spaced apart relationship thereto, means carried by said housings and being operable to detachably secure the ends of the posts to said housings, a cover hinged adjacent each longitudinal edge of the back member 60 and being provided on its inner face with a projection extending toward its adjacent housing, each of said housings being provided with a slot to permit said projection to pass through the housing during opening and closing of the cover, 65 said projections being arranged to engage the leaves and arrange them in right angular relationship to the back member during the closing of the covers.

3. A loose leaf binder comprising a back member, a cover hinged to each longitudinal edge of the back member, a housing arranged adjacent each edge of the back member and extending outwardly at an oblique angle relatively thereto, a plurality of leaf retaining posts, a pintle slide 70

5 mounted in each housing and being provided with post engaging pintles, each of said covers being provided with a plurality of projections extending toward the hinge of the cover, and each of said housings and pintle slides being provided with slots arranged to permit said cover projections to pass from one side of the housing to the

other during the opening and closing of the covers, said cover projections being arranged to engage the leaves in the binder and arrange them in right angular relationship to the back member when the covers are in closed position.
